UNITED STATES PATENT OFFICE.

ERNST LAUSCHKE AND JULIUS SCHMOHL, OF CHICAGO, ILLINOIS, ASSIGNORS
TO BARNHART BROTHERS & SPINDLER, OF SAME PLACE.

DESIGN FOR A FONT OF PRINTING-TYPE.

SPECIFICATION forming part of Design No. 20,244, dated October 28, 1890.

Application filed October 6, 1890. Serial No. 367,275. Term of patent 14 years.

To all whom it may concern:

Be it known that we, ERNST LAUSCHKE and JULIUS SCHMOHL, subjects of the Emperor of Germany, residing at Chicago, county of Cook, and State of Illinois, have invented and produced a new and original Design for a Font of Printing-Type, which is fully set forth in the following specification, reference being had to the accompanying typographical im-
pressions, forming a part thereof.

This design comprises upper and lower case letters, figures, character &, dollar-mark, and points. In general, the letters are quite extended. A strong contrast is presented between the light and heavy lines of each letter, the light lines being substantially hair-lines and the heavy lines being uniform in body, except curves, which merge gradually in hair-lines.

The characteristic of the design is present in nearly all the letters, and consists of a horizontal crescent-swell flourish terminating hair-line, the hair-lines to which such flour-

ish is appended being folded back upon itself in order to receive such terminal flourish, 25 said flourish being within the normal compass of the letter, as distinguished from an exterior flourish.

We claim—

The design for a font of printing-type herein 30 shown and described, wherein the letters have heavy and hair lines and are characterized by horizontal crescent-swell flourishes terminating hair-lines of the body, such hair-lines being folded back upon themselves to receive 35 such terminal flourishes within the normal compass of the letter, substantially as set forth.

In testimony whereof we have hereunto set our hands, at Chicago, this 2d day of October, 40 1890, in the presence of two witnesses.

ERNST LAUSCHKE.
